US00D474803S

(12) **United States Design Patent** (10) Patent No.: **US D474,803 S**
Leu (45) Date of Patent: ** May 20, 2003

(54) **TYPE FONT**

(75) Inventor: **Olaf Leu**, Wiesbaden (DE)
(73) Assignee: **Heidelberger Druckmaschinen AG**,
Heidelberg (DE)
(**) Term: **14 Years**
(21) Appl. No.: **29/150,552**
(22) Filed: **Nov. 14, 2001**

(30) **Foreign Application Priority Data**

May 15, 2001 (DE) 4 01 50 006
(51) LOC (7) Cl. **18-03**
(52) U.S. Cl. **D18/24**
(58) Field of Search D18/24-33; 101/398,
101/399
